UNITED STATES PATENT OFFICE.

WILLIAM H. MILLER, OF BROOKLYN, NEW YORK.

DESIGN FOR A HAMMOCK.

SPECIFICATION forming part of Design No. 25,738, dated June 30, 1896.

Application filed January 14, 1896. Serial No. 575,540. Term of patent 7 years.

To all whom it may concern:

Be it known that I, WILLIAM H. MILLER, a citizen of the United States, residing at Brooklyn, in the county of Kings and State 5 of New York, have invented and produced a new and original Design for Hammocks, of which the following is a specification, reference being had to the accompanying drawing, which forms a part thereof.

10 The drawing forming part of this specification is a perspective view of a hammock suspended and ready for use and which involves my new and original design.

15 The leading feature of my design consists in the body portion A of the hammock, which is composed of network of flexible material, such as is usually employed for this purpose, and a side fringe B, which is composed of similar material, and the lower portion of 20 which is provided with depending tassels C, said fringe being divided at predetermined points by vertical cords D, which are also composed of material similar to that of which

the body portion and the fringe is composed, and the lower ends of which are provided 25 with depending tassels E.

It will be understood that a fringe is provided for each side of the hammock or for each edge thereof, and when the hammock is suspended, as shown in the drawing, the entire design is harmonious and complete and presents a pleasing appearance to the eye. 30

Having fully described my new and original design for hammocks, I claim as new and desire to secure by Letters Patent— 35

The design for hammocks having the body portion ends, head-rest, and depending side fringes as herein shown.

In testimony that I claim the foregoing as my invention I have hereunto signed my 40 name, in presence of two witnesses, this 24th day of December, 1895.

WILLIAM H. MILLER.
